UNITED STATES PATENT OFFICE.

WILLIAM T. DOREMUS, OF NEW YORK, N. Y.

IMPROVEMENT IN ROTARY PUMPS.

Specification forming part of Letters Patent No. 173,215, dated February 8, 1876; application filed January 15, 1876.

To all whom it may concern:

Be it known that I, WILLIAM T. DOREMUS, of the city, county, and State of New York, have invented a new and Improved Rotary Pump, of which the following is a specification:

Figure 1 is a top view of my improved pump; and Fig. 2 is a vertical longitudinal section of the same, taken through the line *x x*, Fig. 1.

Similar letters of reference indicate corresponding parts.

The object of this invention is to furnish an improved rotary pump, delivering a continuous stream of a fluid, and forcing it to any desired distance, and which shall be simple in construction and effective in operation.

The invention consists in an improved rotary pump, in which a fluid is forced through a flexible tube coiled around the face of a cylinder, and receiving and discharging its fluid through the hollow journals of said cylinder by the pressure upon said tube of a second cylinder, as hereinafter fully described.

A represents the frame of the pump, in bearings in which revolves a cylinder, B. The journals of the cylinder B are made hollow to receive a flexible tube, C, made of rubber or other suitable material, which passes in through one journal, passes out through the hub of the cylinder B, passes through a hole or notch in the shell of said cylinder, makes a little more than one turn around it, passes in through a hole or notch in its shell, in through a hole in its hub, and out through its other journal.

The tube C should be swiveled at the ends of the journals of the cylinder B, to prevent it from being twisted by the revolution of said cylinder, and should have a check-valve in its discharge end, to prevent any back flow of the fluid.

The part of the tube C that passes around the cylinder B may be round or flattened, or of any form not liable to be injured by compression.

The flexible tube need not pass through the journals of the cylinder B, but may be connected with the hub of said cylinder, and the fluid received and discharged through its journals,

with the outer ends of which the inlet and discharge pipes may be connected by swiveled joint or otherwise.

D is a cylinder, the journals of which revolve in bearings in a frame or yoke, E, that slides in the frame A, and has a swiveled screw, F, connected with it, so that it may be adjusted to press the tube C against the face of the cylinder B with any desired pressure. To one of the journals of the cylinder B is attached a crank or pulley, G, for the attachment of the power.

The cylinder D may be revolved by friction, or gear-wheels may be attached to the journals of the two cylinders to mesh into each other, so that both cylinders may be revolved with exactly the same velocity. The latter construction is preferred, as it protects the tube from any sliding friction.

The details of construction may be varied in various ways without departing from my invention.

With this construction, as the cylinders B D are revolved the tube C is compressed between their faces, which forces the fluid in front of the point of contact out through the discharge end of the tube C, and forms a vacuum in the rear of said point of contact, into which the fluid is forced by atmospheric pressure, so that there will be a continuous discharge of the fluid from the discharge end of said tube C.

Having thus described my invention, I claim as new and desire to secure by Letters Patent—

The cylinder B, provided with hollow journals, and having a flexible tube, C, coiled around it, with its ends passed through or connected with the said hollow journals, and through which tube and hollow journals a fluid is forced by the pressure upon said tube of a second cylinder, D, substantially as herein shown and described.

WILLIAM T. DOREMUS.
